CLAIM

We claim the ornamental design for a personal hydration system reservoir, as shown and described.

DESCRIPTION

FIG. 1 is a front perspective view of the claimed design.

FIG. 2 is a back perspective view of the claimed design.

FIG. 3 is a front elevation view of the claimed design.

FIG. 4 is a back elevation view of the claimed design.

FIG. 5 is a right side view of the claimed design.

FIG. 6 is a left side view of the claimed design.

FIG. 7 is a top view of the claimed design; and,

FIG. 8 is a bottom view of the claimed design.

The ornamental design which is claimed is shown in solid lines in the drawings. The broken lines in the drawings are for illustrative purposes only and form no part of the claimed design.

The broken lines showing the nozzle in FIGS. 1, 3, 5 and 6, illustrate the portion of the design that form no part of the claim. The upper and lower broken lines on the neck as well as the broken lines on the surface of the article throughout the views form the boundary of the design with the lines themselves and the areas within them forming no part of the claimed design.

1 Claim, 6 Drawing Sheets
